UNITED STATES PATENT OFFICE.

EDMUND S. R. BRANDT, OF NEWPORT, RHODE ISLAND.

SEGMENTAL TURBINE BAND.

Application filed May 9, 1921. Serial No. 468,149.

To all whom it may concern:

Be it known that I, EDMUND S. R. BRANDT, a citizen of the United States, residing at Newport, Rhode Island, have invented new and useful Improvements in Segmental Turbine Bands, of which the following is a specification.

This invention relates to improvements in torpedoes and more particularly to improvements in the turbines used in driving the torpedo. The invention will hereinafter be described with relation to its application to such a turbine although it is, of course, to be understood that the invention is applicable to turbines having other uses.

As is well known to those skilled in the art the turbines used in driving torpedoes particularly include a disc having buckets cut through from one side to the other near the periphery of the disc and these buckets, after being cut, are closed by means of a circumferential band, preferably made in one piece and secured to the disc by flanged overheads of the blades between the buckets. This construction, however, has been open to some objections primarily because, due to heat and high centrifugal speed there was a tendency for the circumferential band to expand and buckle between the so-called rivets or flanged over portions causing an unbalancing of the turbine. It frequently happened that the band loosened at one or more points from its attaching means and would fly outwardly due to centrifugal action and frequently wreck the torpedo.

It is one of the primary objects of the present invention to overcome this objection, among others, by constructing the band in a plurality of individual parts. In this manner each part is individually held and is so spaced from adjacent parts as to permit expansion and contraction without danger of buckling.

A further object is to provide a more reliable and efficient turbine disc than now in use.

With these objects in mind attention is directed to the accompanying sheet of drawing forming part of this disclosure and wherein similar reference characters denote corresponding parts.

Figure 1 is an elevational view of the periphery of the turbine disc showing the buckets in dotted lines and overlapping intervening segments.

Figure 2 is a sectional view, and,

Figures 3, 4, and 5 are detail views of the segments of the band.

Referring now to these drawings in detail, 1 denotes the turbine disc provided at its periphery with transverse curved buckets 2 indicated in dotted lines in Figure 1 which are separated by blades 3 each provided with a flanged head 4 adapted to hold a portion of the segmental peripheral band 5 of the disc.

These portions are generally rectangular in shape as shown in Figure 3 and are provided with intervening overlapping edges as shown in Figures 2 and 4. Thus each part is securely held by its fastening means 6 and the space 6 between adjacent segments permits a certain amount of expansion due to the high temperatures to which the disc is subjected without putting excessive strain on the holding rivets 4 since expansion of each rivet is not transmitted to other parts of the band and is not cumulative as in a continuous band. This prevents expansion strains from increasing the strain on the rivet head 4 due to normal centrifugal force so that there is no tendency of the band to strip from the rivet and fly off since the rivet is amply strong to hold against the centrifugal force due to a peripheral speed of 800,000 inches per minute as shown in tests.

The segments are preferably made of special band steel with two sliding faces to permit movement due to heat of expansion and rotative expansion of the turbine wheel itself which tends to increase the peripheral diameter thus putting a further tensile strain on a continuous band already weakened by heat. This segmental part further provides for neutralizing initial riveting strains as the segments adjust themselves under the riveting process.

Each bucket has its own segment riveted to it instead of being made in one with the bucket. Each bucket is overlapped by two segments one of which is rigidly secured and the other of which slides over the head of the bucket when expanded by heat and under the rigidly secured segment. Each segment maintains gas tight contact with adjacent segments even though each segment moves with reference to adjacent segments.

It will thus be seen that the present invention provides an improved turbine capable of high speeds without danger of stripping the band and wrecking adjacent mechanisms.

Without further analysis, the foregoing

will so fully reveal the gist of this invention that others can by applying current knowledge readily adapt it for various applications without omitting certain features that, 5 from the standpoint of the prior art, fairly constitute essential characteristics of the generic or specific aspects of this invention, and, therefore, such adaptations should and are intended to be comprehended within the 10 meaning and range of equivalency of the following claims.

What I claim is:

1. A turbine wheel provided with peripheral buckets and a continuous band surrounding said wheel and closing the openings between the ends of the buckets, said band being formed of a plurality of independent parts in gas tight and movable contact with each other, one part for each 15 bucket.
2. A turbine wheel provided with peripheral buckets and a continuous band surrounding said wheel and closing the opening between the ends of the buckets, said band being formed of a plurality of independent parts, each part comprising a rectangular piece of metal secured to a single bucket only of the turbine wheel and overlapping the adjacent segment. 25
3. A turbine wheel provided with a plurality of peripheral buckets, a peripheral band enclosing said buckets, said band being formed of a plurality of independent 30

segments, means for securing each segment rigidly to one bucket only on the wheel, such 35 segment overlapping and underlapping the segments at opposite sides respectively.

4. A turbine wheel provided with a plurality of peripheral buckets, a peripheral continuous segmental band, said band being 40 formed of a plurality of independent segments each rigidly secured to a bucket and partially and slidably secured to the next successive bucket under the rigid securing 45 of the next segment.

5. A turbine wheel provided with a plurality of peripheral buckets, a peripheral continuous segmental band, said band being 50 formed of a plurality of independent segments, each such independent segment having sliding contact on inclined surfaces with segments on either side and sliding contact on the next successive bucket under the rigid securing of that bucket segment.

6. A turbine wheel provided with a plurality of peripheral buckets, a peripheral continuous segmental band, said band being 55 formed of a plurality of independent segments, each segment being free to expand peripherally over and under adjoining segments without destroying the continuity of 60 the whole band.

Signed at Newport, Rhode Island, this 21 day of March, 1921.

E. S. R. BRANDT.
